UNITED STATES PATENT OFFICE.

CLARENCE L. DEWEY, OF MICHIGAN CITY, INDIANA, ASSIGNOR TO CEMENT-GUN COMPANY, INC., OF ALLENTOWN, PENNSYLVANIA, A CORPORATION OF NEW YORK.

HOLDING CLIP FOR CONCRETE REINFORCEMENT.

Application filed December 26, 1923. Serial No. 682,727.

The invention relates to certain new and useful improvements in holding clips for concrete reenforcement.

One of the objects of the invention is to provide an improved mesh spacer or wire chair for supporting the reenforcing structure of concrete members, especially in perpendicular surfaces, before the cementitious material is applied to the same, and before it is set.

Another object is to provide a combined supporting and spacing means for concrete reinforcements, where the concrete is distributed by a cement gun; and one that will be completely filled up with the cement.

A further object is to furnish a simple mesh spacer constructed entirely of metal wire that can be easily and quickly fastened to the supporting member by a common nail or the like.

A still further object is to provide a spacer that can be compressed, or knocked down, from its normal height while it is being placed in position, so that practically any depth of reenforcement may be made by one size of clip.

With these various objects in view, my invention consists of the novel features of construction, combination and arrangement of parts hereinafter fully described, pointed out in the claims and shown in the accompanying drawings in which similar parts have similar numerals of reference attached thereto:

Figure 1 is a side elevation of the preferred embodiment of the invention.

Fig. 2 is a front elevation.

Fig. 3 is a top plan view.

Fig. 4 shows the mesh spacer in position.

Referring now to these drawings, 1 represents my improved wire chair or mesh spacer which comprises, when positioned as more particularly shown in Fig. 4, a horizontally placed U or loop 2, merging into two vertically placed U's or loops 3 and 4, one on each side of the said first mentioned loop 2. The continuation 5 of the loop 3, and the continuation 6 of the loop 4 then extend horizontally and practically parallel; the right hand one 5 extending forward to about the further end of the horizontal loop 2, then perpendicularly downward as at 7 to the floor 8, and then backward as at 9 to about the outer periphery of the right hand

vertical loop 3, but spread to the right. The 55 left hand horizontal portion 6 extends forward horizontally, but only for a short distance bending abruptly backward and diagonally downward as at 10 to the floor, and then extending forward as at 11 to about 60 the same length as the right hand leg or member 9. This leg 9 is also bent sideways to the left, the two legs being spread apart about equally, as shown more particularly in Fig. 2.

In operating the invention, the reenforcing members as 12 are placed over the temporary wooden backing 13, and are held in place by my herein-described mesh spacer 1, one of the said reenforcing members being shown 70 in Fig. 4 partly encircled by the two side by side vertical U's or loops 3 and 4. A common nail 14 or screw or the like, is then inserted through the upper loop 2 and driven into the backing of wall, floor or ceiling. 75 The reenforcement now being held in position cementitious material or the like is either laid over and between the said members manually or by the well known cement gun; and it will be at once seen that the 80 liquid or plastic material will fill up all around the mesh spacer in every direction, as there are no flat parallel sides into which the material might not, and often does not run.

Instead of requiring several sizes of clips for different thicknesses of reenforcement as with other chairs, one size will do. For the nail can be driven into the wood backing more and more, spreading the legs 7 and 10 further and further apart and thus reducing the height of the reenforcing members 90 12 from the backing 13.

If the entire wall, floor or ceiling had been overlaid by the reenforcing members to a certain height from the backing and the cementitious material had not yet been laid, and it were desired to have said height from the backing less, all of the nails in place could be driven in still further and the legs 7 and 10 spread further apart as at 15, Fig. 2, and the whole set of reenforcing members would be pushed down thereby nearer the backing.

This mesh spacer can also be made up 105 in large sizes for concrete reenforcing bars, as it is very easy to insert, and then depress or knock the bend or loop 2, which nor-

mally lies over the top of the reenforcing bar, down over the same, as at 16 in Fig. 1, and this will hold the bar tightly in place, and there will be no shifting or turning over, 5 as is liable to happen in other chairs.

As my invention is in some of its aspects generic, I do not limit myself to the details as shown and described, but also contemplate the employment of suitable equivalents 10 that fairly fall within the scope of my claims.

In this connection I may state that I may make the two forwardly extending members 5 and 6 of the same length, and 15 the loops 2, 3 and 4 smaller if desired.

Therefore it will be understood that I may make various changes in the detail, form, size and proportion as well as the number and position of the several parts, without 20 parting from the spirit of the invention.

I claim:

1. A mesh spacer comprising a single piece of wire having a horizontal loop, two contiguous vertical loops, and a leg depending 25 from each of the said last mentioned loops, one of the said legs having a foot

pointing forward and the other leg having a foot pointing backward.

2. A mesh spacer comprising a single piece of wire having a horizontal loop, two contiguous vertical loops, a leg portion extending downwardly from one of the last mentioned loops, a portion extending horizontally from the other of said loops, a leg portion extending downwardly from the end 30 of said horizontal portion, and foot portions extending horizontally in opposite directions from the ends of said leg portions. 35

3. A mesh spacer comprising a single piece of wire having three contiguous open 40 loops, two of said loops being arranged in planes substantially parallel with each other and substantially perpendicular to the plane of the third loop, leg members extending from each of the two first mentioned loops 45 in directions away from the third loop, and foot portions at the ends of said leg members and lying in a plane parallel with the plane of the third loop.

In testimony whereof I hereby affix my 50 signature.

CLARENCE L. DEWEY.
